UNITED STATES PATENT OFFICE.

ELLIS M. BURR, OF CHAMPAIGN, ILLINOIS.

CHANGEABLE-SPEED GEARING.

No. 813,770.

Specification of Letters Patent.

Patented Feb. 27, 1906.

Application filed July 1, 1905. Serial No. 267,964.

To all whom it may concern:

Be it known that I, ELLIS M. BURR, a citizen of the United States, residing at Champaign, in the county of Champaign and State 5 of Illinois, have invented certain new and useful Improvements in Changeable-Speed Gearing, of which the following is a specification.

My invention is concerned with a novel 10 mechanism by which the motion of a shaft rotating at uniform speed can be transformed into the motion of another shaft rotating at different speeds or in different directions.

15 My invention is designed, primarily, for use in driving an automobile, and I have shown it arranged so that from the shaft rotating at a uniform speed in one direction I can drive the machine forward at any one of 20 three different speeds or backward at a certain speed.

25 My invention is embodied in a structure for the purpose described that is exceedingly simple and efficient in operation as well as inexpensive to construct.

30 My invention is further concerned with novel connections by which the aforesaid or similar gearing can be controlled by a lever placed conveniently to the driver and by 35 which he can set the gearing in any of the desired speeds or directions and securely lock it from accidental displacement.

35 To illustrate my invention, I annex hereto four sheets of drawings, in which the same reference characters are used to designate identical parts in all the figures, of which—

40 Figure 1, is a top plan view of the frame of an automobile having my invention applied thereto, the gearing being shown in full lines as adjusted for the highest rate of speed and in the dotted lines as adjusted for the intermediate rate of speed. Fig. 2 is a view similar to Fig. 1, but with the gearing shown in full lines as adjusted for the slow speed forward and in dotted lines as adjusted for the same rate of speed backward. Fig. 3 is a central horizontal vertical section through the gearing on the line A A of Fig. 4. Fig. 4 is a vertical section on the line B B of Fig. 3. 45 Fig. 5 is an end elevation of the shifting lever and connections. Fig. 6 is a side elevation of the same. Fig. 7, Sheet 2, is a detail view of a portion of the shifting lever, showing the spring for holding the lock in place. 50 Fig. 8 is a detail in section on the line C C of Fig. 2; and Fig. 9, Sheet 3, is a detail in verti-

cal section, on an enlarged scale, on the line D D of Fig. 1.

I have shown the gearing and the operating-lever and connections mounted in the frame of an automobile, which frame is shown as rectangular and made up of the side pieces 10 and 11 and the front and rear end pieces 12 and 13. These pieces are secured together in any desired manner and suitably braced, as shown. Where the invention is used in an automobile, the power is preferably applied first to the fly-wheel shaft 14, which is shown as journaled in suitable bearings 15 and 16, formed in or secured upon the end piece 12 and the cross-piece 17. A universal joint 18 connects the inner end of this shaft to an intermediate section 19 of the driving-shaft, the other end of which is connected by the universal joint 20 to the rear section 21 of the driving-shaft. This rear section 21, as best shown in Figs. 3 and 4, has an elongated bearing-sleeve 22, the rear end of which is secured in the collar 23 of the yoke 24, the yoke 24 having the two arms 25 of the fork, which are preferably circular in cross-section and which are adapted to slide back and forth in the similarly-shaped apertures formed in the bearing-blocks 26, which are pivotally secured in the side pieces of the U-shaped frame 27, the rear end of which is secured to the inner side of the rear wall of the frame 28, which carries the bearings 29 and 30 for the rear axle 31. I have shown this rear axle as continuous for convenience of illustration; but it will be understood that it may be divided and provided with the customary equalizing-gear, which is intended to be mounted in the space 32, formed in the frame 28 on that portion of the shaft which is shown as surrounded by the collar 33.

I have illustrated the bearings 29 and 30 as being provided with the rollers 34; but it will be understood that they form no part of my invention.

The shaft or axle 31 has secured thereon the oppositely-facing bevel gear-wheels 35 and 36, which are preferably secured to the hub 37, which in turn is secured to the shaft 31. The rear section 21 of the driving-shaft has secured thereon to rotate therewith the three bevel gear-pinions 38, 39, and 40, the pinion 40 being the largest and used for the highest speed, the pinion 39 being intermediate and used for intermediate speed, and the pinion 38 being the smallest and used for the slow speed and being adapted to engage with

either the gear-wheel 35 for forward movement or with the gear-wheel 36 for backward movement. I might arrange the other pinions 39 and 40 so as to engage with either 5 wheel, if desired; but as only the slow speed is needed for backing an automobile I have shown only the pinion 38 as arranged to engage with the wheel 36. For convenience of 10 construction I have shown the pinion 38 as cut on the end of the sleeve 41, which surrounds a portion of the bearing-sleeve 22 and which is secured to the shaft 21 by the spline 42. The bevel-pinions 39 and 40 are secured 15 on the sleeve 41, and the thrust-bearing for the bearing-sleeve 43, in which the sleeve 41 is journaled, is formed by the antifriction-balls 44, mounted in the customary collar 45, which is placed between the bearing-surface on the base of the pinion 40 and the 20 bearing-surface formed on the flange 46, forming the inner end of the bearing-sleeve 43.

To securely hold the pinion 38, 39, or 40, as the case may be, in mesh with the wheel 25 35 or 36, as the case may be, I provide one or more plates 47 and 48, a top and bottom plate being shown, as seen in section in Fig. 4. These plates are secured to the forward portion of the frame 28 and have the ends of the 30 frame 27 secured thereto, as shown in Fig. 4. These plates 47 and 48 have the recessed slots 49 formed therein and consisting of the slow-speed forward notch 50, the slow-speed rearward notch 51, the medium-speed forward notch 52; and the high-speed forward notch 53, these notches being connected by the straight passage 54 and the notches 50, 51, and 52 being elongated and on the arc of a circle whose center is the axis of the pivoted bearings 26. The bearing-sleeve 43 has the bosses 55 and 56 projecting downwardly and upwardly therefrom and whose top and bottom surfaces engage with the adjacent surfaces of the plates 47 and 48. Guiding-pins 57 and 58 are secured in these bosses 45 55 and 56 and pass through the recessed apertures 49, so that the pinions 38, 39, and 40 will be properly guided in bringing them into and out of engagement.

50 Where the invention is to be used with automobiles, it is necessary to provide some means for changing the gearing adjacent the driver's seat, and for this purpose I employ the hand-lever 59, which is pivotally mounted by the pin 60 on the flattened end 61 of the rock-shaft 62, which is journaled in suitable bearings carried by the side pieces 10 and 11 and held from longitudinal movement therein by the collars 63 and 64, secured thereon just inside of the bearings. The lever 59 has the elongated slot 65 formed therein, through which the flattened end 61 of the rock-shaft 62 passes, and it will be apparent that when the lever is rocked in the 60 direction of the length of the vehicle the shaft

62 will be rocked. The shaft 62 is preferably supported intermediate the end bearings by a bearing formed in the bracket 66, and secured to the shaft adjacent this bracket 66 is the crank-arm 67, to the outer end of which is pivoted the link 68, whose rear end is pivotally connected to the bell-crank 69, which is pivoted on the cross-piece 70 of the frame. The longitudinal arm of the bell-crank 69 is much longer than the transverse 75 arm and has the elongated slot 71 formed in the end thereof, and through this slot 71 passes the bolt 72, which is secured at its upper and lower ends to the left-hand ends of the shifting levers 73 and 74, the upper lever 73 being pivotally mounted on the pin 58, while the lower lever 74 is pivotally mounted on the pin 57, both levers being just outside of and bearing on their respective plates 48 and 47. The right-hand ends of these floating levers 73 and 74 are connected by the pin or bolt 75, which has pivoted thereon the link 76, the forward end of which is pivoted on the transverse arm of the bell-crank 77, fulcrumed on the cross-piece 78. The other 90 arm of the bell-crank 77 has the link 79 pivoted thereto, the other end of which is pivoted to the lower end of the lever 59. By an examination of Figs. 1 and 2 it will be seen that when the lever 59 is swung in a plane 95 longitudinally of the frame it will, through the rock-shaft 62, bell-crank 69, and connections, move the levers 73 and 74 transversely of the frame, whereas when the lever 59 is swung transversely of the frame it will, through the bell-crank 77 and the link connections, move the levers 73 and 74 longitudinally of the frame. By the combined movements of the lever 59 it will be apparent that the levers 73 and 74 can be shifted into 100 any necessary positions to bring the pins 105 either into the notch 53, in which the vehicle moves forward at full speed, in the notch 52, in which the vehicle moves forward at medium speed, in the notch 50, in which it moves forward at slow speed, or in the notch 51, in which it moves backward at slow speed. The movements in the two directions are combined, as it were, and guided by the slots 110 of the recessed plate 80, which is curved, as 115 shown in Fig. 6, and is secured by the brackets 81 and 82 upon the side piece 11 of the frame. The plate 80 is provided with the recess or notch 83, corresponding to the notch 53, the notch 84, corresponding to the notch 52, the notch 85, corresponding to the notch 50, and the notch 86, corresponding to the notch 51, and these notches are connected by a passage 120 through which the adjacent portion of the lever 59 moves. By means of the connections here shown and the two guiding plates with their notches I am enabled by the moving of the lever 59 to move the levers 73 and 74 so as to bring the pinions into any desired engagement to secure the desired speed. 125 130

I preferably arrange to lock the pinions in engagement in connection with the plates 47 and 48, as well as through the medium of the lever 59, being locked by means of the spring-pressed lug 87 engaging the apertures 88, 89, and 90 adjacent the recesses 83, 84, and 85. The lug 87 is formed on the outer end of the yoke-shaped lever 91, which embraces the lever 59 and is pivoted at 92 to a collar 93, secured on said lever. A link 94, pivoted to the lever 91, extends upward along the lever 59 to the handle 95, which embraces the upper end of the lever 59 and is pivoted thereto at 96. A helically-coiled expanding-spring 97, secured in the tube constituting the body of the lever 59, presses down on the upper side of the pin 98, extending across the yoke of the lever 91, and through a slot 99, formed in the handle 59. The action of the spring 97 on the lever 91, thus serves to hold the lug 87 in engagement with whichever aperture is adjacent to the notch in the plate 80, in which the lever 59 is set. This mechanism locks the lever, and it can be released, as will be apparent, by pressing the handle 95 toward the lever 59. The pin 98 has secured thereto the link 100, which extends downwardly through the inside of the tube constituting the body of the lever 59 and is pivoted to the horizontal arm of the bell-crank 101, which is pivoted to the lug 102, formed on the side of the lever 59. The vertical arm of the bell-crank 101 is offset, as seen at 103, so that the link 104, pivoted to the outer end thereof, is brought outside of the lever 59 and the rock-shaft 62. The link 104 is pivotally connected at its other end to the bell-crank 105, which is pivoted on the bracket 106, projecting inwardly from the side piece 10. The transverse arm of the bell-crank 105 has the link 107 pivoted thereto, and this link extends rearwardly and is pivoted to the vertical arm of a bell-crank lever 108, fulcrumed on a bracket secured to the frame 28, the horizontal arm of the bell-crank 108 extending forwardly and underneath the bottom of the sliding spring-pressed locking-bolt 109, (best shown in Fig. 9,) which slides in a bearing formed in the casing 110, which is pivoted by the pin 111 passing through an ear 112, formed on or secured to the adjacent side of the frame 28, and also through the ears 113 and 114, formed on the casing 110. The levers 73 and 74 are mounted to slide through bearings formed in the top and bottom of the casing 110, as shown in Fig. 9, and are provided with the notches 115, 116, 117, and 118. The sliding bolt 109 is provided with the notches 119 and 120 and is normally held downward by the helically-coiled tensile spring 121, extending between the pin 122, secured to the top of the bolt 109, and the pin 123, extending from the side of the casing 110. When the pinion 38 engages the wheel 35 and the pins 57 and 58 are in the re-

cesses 50, the notches 118 are in register with the sliding bolt 109, which locks them in place. Similarly, when the pinion 38 is in engagement with the wheel 36 and the pins 57 and 58 are in the recess 51 the locking-notches 115 are in position to be engaged by the locking-bolt 109. The locking-notches 116 will be engaged by the locking-bolt 109 when the pinion 40 engages the wheel 35 for full speed, and the notches 117 will be engaged by the locking-bolt when the pinion 39 engages the wheel 35 for intermediate speed. When the speed is to be changed, the operator pulls the handle 95 to the lever 59, disengaging the locking-lug 87, and through the action of the link 100, bell-crank 101, link 104, bell-crank 105, link 107, and bell-crank 108 lifting the locking-bolt 109 and releasing the floating levers or bars 73 and 74, so that the lever 59 can be brought to any other necessary position to make the desired engagement of the gears. When they are properly engaged, the handle 95 is released, and the action of the springs 97 and 121 will serve to lock the parts in their new position.

While I have shown and described my invention as embodied in the form which I at present consider best adapted to carry out its purposes, it will be understood that it is capable of modifications and that I do not desire to be limited in the interpretation of the following claims except as may be necessitated by the state of the prior art.

What I claim as new, and desire to secure by Letters Patent of the United States, is—

1. In a device of the class described, the combination with the bevel gear-wheel, of a bearing-sleeve pivoted on the axis of the wheel, a shaft journaled in said sleeve, a plurality of different-sized beveled pinions secured to said shaft, and means for holding said shaft with any desired one of said pinions in engagement with the wheel.

2. In a device of the class described, the combination with a pair of inwardly-facing bevel gear-wheels, of a bearing-sleeve pivoted on the axis of and between said wheels, a shaft journaled in said sleeve, a plurality of different-sized bevel-pinions secured to said shaft, and means for holding said shaft with one of said pinions in engagement with one or the other of said wheels.

3. In a device of the class described, the combination with a pair of inwardly-facing bevel gear-wheels, of a bearing-sleeve pivoted on the axis of and between said wheels, a shaft journaled in said sleeve, a plurality of different-sized bevel-pinions secured to said shaft, and means for holding said shaft with one of said pinions in engagement with one of said wheels, or with any one of said pinions in engagement with the other of said wheels.

4. In a device of the class described, the combination with the bevel-gear-wheel, of a

bearing - sleeve pivoted on the axis of the wheel, a shaft journaled in said sleeve, a plurality of different-sized bevel-pinions secured to said shaft, and means for holding said shaft with any desired one of said pinions in engagement with the wheel, consisting of a bearing-sleeve for the outer end of said shaft, a pin carried by said sleeve, and a slotted recessed plate with which the pin coöperates.

10. 5. In a device of the class described, the combination with the bevel gear-wheel, of a bearing - sleeve pivoted on the axis of the wheel, a shaft journaled in said sleeve, a plurality of different-sized bevel-pinions secured to said shaft, and means for holding said shaft with any desired one of said pinions in engagement with the wheel consisting of a bearing-sleeve for the outer end of said shaft, two oppositely - extending pins carried by 15 said bearing - sleeve, and a pair of similarly slotted and recessed plates between which the outer sleeve slides.

6. In a device of the class described, the combination with the pair of inwardly-facing bevel gear-wheels, of a bearing-sleeve pivoted 20 between and on the axis of said wheels, a shaft journaled in said sleeve, a plurality of different-sized bevel-pinions secured to said shaft, a second bearing-sleeve for the outer 25 end of said shaft, a pair of similarly slotted and recessed plates between which the outer sleeve slides, and a pair of oppositely-extending pins secured to the outer bearing-sleeve and extending through the slots in the plates, 30 all combined and operating substantially as 35 and for the purpose described.

7. In a device of the class described, the combination with the pair of inwardly-facing bevel gear-wheels, of a bearing-sleeve pivoted 40 between and on the axis of said wheels, a shaft journaled in said sleeve, a bevel-pinion secured to said shaft, a second bearing-sleeve for the outer end of said shaft, a pair of similarly slotted and recessed plates between 45 which the outer sleeve slides, and a pair of oppositely - extending pins secured to the outer bearing-sleeve and extending through the slots in the plates, all combined and operating substantially as and for the purpose described.

8. In a device of the class described, the combination with the bevel gear-wheel, of a bearing - sleeve pivoted on the axis of the wheel, a shaft journaled in said sleeve, a plurality of different-sized bevel-pinions secured 55 to said shaft, means for holding said shaft with any desired one of said pinions in engagement with the wheel, and a lock for said means to prevent any possible disengagement of the pinions.

9. In a device of the class described, the combination with the bevel gear-wheel, of a bearing-sleeve pivoted on the axis of the wheel, a shaft journaled in said sleeve, a plurality of different-sized bevel-pinions secured 60

to said shaft, a bearing-sleeve for the outer end of said shaft, a pin carried by said sleeve, a slotted recessed plate with which the pin coöperates, a member moving with said outer sleeve and having a number of recesses corresponding to the pinions, a stationary bearing through which said member moves, and a locking-bolt coöperating with said recesses. 70

10. In a device of the class described, the combination with the bevel gear-wheel, of a bearing-sleeve pivoted on the axis of the wheel, a shaft journaled in said sleeve, a plurality of different-sized bevel-pinions secured to said shaft, a bearing-sleeve for the outer end of said shaft, a pair of similarly-slotted 75 and recessed plates between which the outer sleeve slides, oppositely-extending pins secured to said outer sleeve and extending through the slots in the plates, a pair of members moving with said sleeve and secured to the pins and having a plurality of recesses equal in number to the pinions, a pair of bearings through which said members move, and a locking-bolt sliding adjacent 80 said bearings and coöperating with said recesses. 85

11. In a device of the class described, the combination with the bevel gear-wheel, of a bearing - sleeve pivoted on the axis of the wheel, an inner shaft - section journaled in 90 said sleeve, a plurality of a different-sized bevel-pinions secured to said shaft-section, means for holding said shaft-section with any desired one of said pinions in engagement with the wheel, the outer shaft-section journaled in stationary bearings, and the intermediate shaft-section connected by universal joints to the other shaft-sections. 95

12. In a device of the class described, the combination with the bevel gear-wheel, of a bearing-sleeve pivoted on the axis of the wheel, a shaft-section journaled in said sleeve, a bevel-pinion secured to said shaft-section, means for holding said shaft-section with the pinion in or out of engagement with the wheel, an outer shaft-section journaled in stationary bearings, and an intermediate shaft-section connected by universal joints to the other two shaft-sections. 100

13. In a device of the class described, the combination with the pair of inwardly-facing bevel gear-wheels, of a bearing-sleeve pivoted between the wheels on the axis thereof, a shaft-section journaled in said sleeve, a bevel-pinion secured to said shaft-section, 110 means for holding said shaft-section with the pinion in engagement with one or the other of said wheels, an outer shaft-section journaled in stationary bearings, and an intermediate shaft-section connected by universal joints to the other shaft-sections. 115

14. In a device of the class described, the combination with the pair of inwardly-facing bevel gear-wheels, of a bearing-sleeve pivoted between and on the axis of the wheels, a 120

- shaft-section journaled in said sleeve, a plurality of different-sized bevel-pinions secured to said shaft, means for holding said shaft-section with one of said pinions in engagement with one of said wheels, or with any one of said pinions in engagement with the other of said wheels, an outer shaft-section journaled in stationary bearings, and an intermediate shaft-section connected by universal joints to the other sections.
15. In a device of the class described, the combination with the bevel gear-wheel, of a bearing-sleeve pivoted on the axis of the wheel, a shaft journaled in said sleeve, a plurality of different-sized bevel-pinions secured to said shaft, means for holding said shaft with any desired one of said pinions in engagement with the wheel, a shifting lever, and connections between said shaft and lever whereby any desired one of said pinions can be brought into engagement with the wheel.
20. In a device of the class described, the combination with a bevel gear-wheel, of a bearing-sleeve pivoted on the axis of the wheel, a shaft journaled in said sleeve, a plurality of different-sized bevel-pinions secured to said shaft, a bearing-sleeve for the outer end of said shaft, a pin carried by said sleeve, a slotted recessed plate with which the pin coöperates, a shifting lever, and connections between said lever and pin whereby the bearing-sleeve may be shifted to bring any desired one of said pinions in engagement with the wheel.
25. 17. In a device of the class described, the combination with the bevel gear-wheel, of a bearing-sleeve pivoted on the axis of the wheel, a shaft journaled in said sleeve, a plurality of different-sized bevel-pinions secured to said shaft, a bearing-sleeve for the outer end of said shaft, a pin carried by said sleeve, a slotted recessed plate with which the pin coöperates, a shifting lever, connections between said lever and pin whereby any desired one of said pinions may be brought into engagement with the wheel, and a guiding-plate for said lever slotted similarly to the recessed plate with which the pin coöperates.
30. 18. In a device of the class described, the combination with the bevel gear-wheel, of a bearing-sleeve pivoted on the axis of the wheel, a shaft-section journaled in said sleeve, a plurality of different-sized bevel-pinions secured to said shaft, a bearing-sleeve for the outer end of said shaft, a pin carried by said sleeve, a slotted recessed plate with which the pin coöperates, a shifting lever, connections between said lever and bearing-sleeve whereby any desired one of said pinions may be brought into engagement with the wheel, and connections between the shifting lever and locking-bolt whereby the bolt may be operated to release the member.
35. 19. In a device of the class described, the combination with the bevel gear-wheel, of a bearing-sleeve pivoted on the axis of the wheel, a shaft-section journaled in said sleeve, a plurality of different-sized bevel-pinions secured to said shaft, means for holding said shaft-section with any desired one of said pinions in engagement with the wheel, an outer shaft-section journaled in stationary bearings, an intermediate shaft-section connected by universal joints to the other sections, a shifting lever, and connections between said lever and means whereby the pinions may be engaged and disengaged as desired.
40. 20. In a device of the class described, the combination with the bevel gear-wheel, of a bearing-sleeve pivoted on the axis of the wheel, a shaft journaled in said sleeve, a plurality of different-sized bevel-pinions secured to said shaft, a bearing-sleeve for the outer end of said shaft, a pin carried by said sleeve, a slotted recessed plate with which the pin coöperates, a shifting lever, connections between said lever and bearing-sleeve whereby any desired one of said pinions may be brought into engagement with the wheel, and a guiding-plate for said lever slotted similarly to the recessed plate with which the pin coöperates.
45. 21. In a device of the class described, the combination with the bevel gear-wheel, of a bearing-sleeve pivoted on the axis of the wheel, a shaft journaled in said sleeve, a plurality of different-sized bevel-pinions secured to said shaft, a bearing-sleeve for the outer end of said shaft, a pin carried by said sleeve, a slotted recessed plate with which the pin coöperates, a shifting lever, connections between said lever and bearing-sleeve whereby any desired one of said pinions may be brought into engagement with the wheel, a guiding-plate with which the lever coöperates, slotted similarly to the recessed plate with which the pin coöperates, apertures in the guiding-plate, and a spring-pressed plunger carried by the lever coöperating with said apertures.
50. 22. In a device of the class described, the combination with the bevel gear-wheel, of a bearing-sleeve pivoted on the axis of the wheel, a shaft journaled in said sleeve, a plurality of different-sized bevel-pinions secured to said shaft, a bearing-sleeve for the outer end of said shaft, a pin carried by said sleeve,

a slotted recessed plate with which the pin coöperates, a shifting lever, connections between said lever and bearing-sleeve for bringing any desired one of said pinions into engagement with the wheel, and means for locking the lever and the bearing-sleeve each in their adjusted position.

23. In a device of the class described, the combination with the bevel gear-wheel, of a bearing-sleeve having forked ends, pivoted bearings on the axis of said wheel through which the forks of the bearing-sleeve slide, a shaft journaled in said sleeve, a plurality of different-sized bevel-pinions secured to said shaft, and means for holding said shaft with any desired one of said pinions in engagement with the wheel.

24. In a device of the class described, the combination with the bevel gear-wheel, of a bearing-sleeve pivoted on the axis of the wheel, a shaft journaled in said sleeve, a plurality of different-sized bevel-pinions secured to said shaft, a bearing-sleeve for the outer end of said shaft, a pin carried by said sleeve, a slotted recessed plate with which the pin coöperates, a member connected with said pin, a rock-shaft a lever pivoted on said rock-shaft to swing in the plane of the axis of the rock-shaft or at an angle thereto to rock said shaft, connections between said member and rock-shaft to move the member in one plane, and connections between said member and the lever to move the member in another plane.

25. In a device of the class described, the combination with the bevel gear-wheel, of a bearing-sleeve pivoted on the axis of the wheel, a shaft journaled in said sleeve, a plurality of different-sized bevel-pinions secured to said shaft, a bearing-sleeve for the outer end of said shaft, a pin carried by said sleeve, a slotted recessed plate with which the pin coöperates, a member connected with said pin, a rock-shaft a lever pivoted on said rock-shaft to swing in the plane of the axis of the rock-shaft or at an angle thereto to rock said shaft, connections between said member and rock-shaft to move the member in one plane, and connections between said member and the lever to move the member in another plane, said connections consisting of links

and bell-cranks, substantially as shown and described.

26. In a device of the class described, the combination with the bevel gear-wheel, of a bearing-sleeve pivoted on the axis of the wheel, a shaft journaled in said sleeve, a plurality of different-sized bevel-pinions secured to said shaft, a bearing-sleeve for the outer end of said shaft, a pin carried by said sleeve, a slotted recessed plate with which the pin coöperates, a member connected with said bearing-sleeve, a rock-shaft a lever pivoted on said rock-shaft to swing in the plane of the axis of the rock-shaft or at an angle thereto to rock said shaft, connections between said member and rock-shaft to move the member in one plane, a bell-crank pivoted between said member and lever, a link connecting the lever and one end of said bell-crank, and a link connecting the other end of said bell-crank and said member.

27. In a device of the class described, the combination with the bevel gear-wheel, of a bearing-sleeve pivoted on the axis of the wheel, a shaft journaled in said sleeve, a plurality of different-sized bevel-pinions secured to said shaft, a bearing-sleeve for the outer end of said shaft, a pin carried by said sleeve, a slotted recessed plate with which the pin coöperates, a member connected with said bearing-sleeve, a rock-shaft a lever pivoted on said rock-shaft to swing in the plane of the axis of the rock-shaft or at an angle thereto to rock said shaft, connections between said member and the lever to move the member in one plane, and connections between said member and the rock-shaft to move the member in another plane, said connections consisting of the crank-arm carried by the rock-shaft, a link pivoted to said crank-arm, a bell-crank to one arm of which the other end of said link is pivoted, and connections between the other arm of said bell-crank and said member.

In witness whereof I have hereunto set my hand this 26th day of June, 1905.

ELLIS M. BURR.
